[57] CLAIM

The ornamental design for a magnetic water softener, as shown and described.

DESCRIPTION

FIG. 1 is a perspective view of a magnetic water softener showing my new design;

FIG. 2 is a top plan view thereof;

FIG. 3 is a side elevational view thereof, the opposite side being identical;

FIG. 4 is a bottom plan view thereof;

FIG. 5 is an end elevational view thereof, the opposite end being a mirror image; and

FIG. 6 is a perspective view thereof, on a reduced scale, the broken line drawing of a water pipe is shown for illustrative purposes only and forms no part of the claimed design.

FIG. 1

FIG. 2

FIG. 3

FIG. 4

FIG. 5

FIG. 6
